UNITED STATES PATENT OFFICE.

ROBERT J. MITCHELL, OF CENTRAL FALLS, RHODE ISLAND.

NIPPLE-HOLDING DEVICE.

1,231,775.

Specification of Letters Patent.

Patented July 3, 1917.

Application filed March 17, 1915. Serial No. 14,960.

To all whom it may concern:

Be it known that I, ROBERT J. MITCHELL, a citizen of the United States, residing at Central Falls, in the county of Providence and State of Rhode Island, have invented certain new and useful Improvements in Nipple-Holding Devices; and I do hereby declare the following to be a full, clear, and exact description of the invention, such as will enable others skilled in the art to which it appertains to make and use the same.

The invention relates to a nipple holding device.

The object of the present invention is to provide a simple, practical and inexpensive device of strong and durable construction adapted for use either in a shop or while out on a job and capable of enabling small pieces of pipe from one-quarter of an inch to six inches in length to be readily threaded without liability of jamming the threads.

A further object of the invention is to provide a nipple holding device adapted to be held in a square jaw vise or pipe vise and capable of securely gripping a piece of pipe at the end edges thereof and of enabling the pipe after threading to be released without putting a pipe wrench on the nipple.

With these and other objects in view the invention consists in the construction and novel combination and arrangement of parts hereinafter fully described, illustrated in the accompanying drawings and pointed out in the claim hereto appended, it being understood that various changes in the form, proportion and minor details of construction may be resorted to without departing from the spirit or sacrificing any of the advantages of the invention.

40 In the drawing

Figure 1 is a longitudinal sectional view of a nipple holding device constructed in accordance with this invention,

45 Fig. 2 is a detail view of the relatively fixed sleeve,

Fig. 3 is a transverse sectional view on the line 3—3 of Fig. 1.

Like numerals of reference designate corresponding parts in all the figures in the 50 drawing.

In the accompanying drawing in which is illustrated the preferred embodiment of the invention, the nipple holding device comprises in its construction, a rod 1 constructed of suitable metal and provided with a reduced front portion 2 adapted to receive a

relatively fixed sleeve 3 which is provided at its inner end edge with saw teeth 4 adapted to engage the forward or outer end of a short piece of pipe or nipple 5. The relatively fixed sleeve 3 which is detachably secured on the reduced portion 2 of the bolt 1 by a nut 6 projects outwardly beyond the circumference of the bolt and is of greater diameter than the same to engage the said pipe or nipple 5 which fits on the outer or front portion of the bolt 1 as shown. The inner or rear end of the pipe or nipple 5 is engaged by the front or outer end of a reduced cylindrical portion 7 of a relatively 70 adjustable supporting sleeve 8 mounted on the bolt 1 and adapted to be clamped in a squared jaw vice or a pipe vise for supporting the nipple holder in position for threading the nipple or pipe 5. The inner or rear portion 9 of the supporting sleeve 8 is preferably square and the reduced cylindrical portion 7 is provided at the front or outer end with saw teeth 10 which engage the pipe or nipple 5 at the inner or rear end edge 80 thereof. By this construction the pipe or nipple 5 is securely gripped at the end edges so that there is no liability of jamming or otherwise injuring the screw threads and as the pipe or nipple is of 85 greater thickness than the reduced portion 7 of the supporting sleeve 8 and projects beyond the face of the relatively fixed sleeve 3, the said pipe or nipple 5 is adapted to be threaded without the die coming in contact 90 with any portion of the nipple holding device. The rear end of the bolt or rod 1 is threaded at 11 for a suitable distance and receives a nut 12 preferably of hexagonal form.

The threaded portion 11 is of sufficient length to permit the relative adjustment of the holding sleeve or supporting sleeve 8 and the bolt to engage short pieces of pipe of various lengths, say from three-quarters of an inch to six inches and the nipple holder enables such short pieces of pipe which are usually consigned to the waste to be threaded and used as nipples.

In the operation of the device the die 105 stock is placed over the outer portion of the nipple or pipe 5 by being passed over the sleeve 3 and when it is desired to remove the nipple or pipe 5 the nut 12 loosened. In arranging the nipple or pipe 5 110 on the rod 1 it is slipped thereon from the rear end of the said rod and the support-

ing sleeve 8 is then placed in position on the rod and the nut 12 screwed against the rear end of the square portion 9 whereby the 5 nipple or pipe is securely fastened or held on the bolt and is firmly maintained in position while being threaded.

The device may be made in various sizes to hold pipes or nipples of different diameters.

10 What is claimed is:

A nipple-holding device comprising a rod for supporting a pipe having a reduced screw threaded front portion, a relatively fixed sleeve located on said reduced portion 15 and of a greater diameter than the rod so as to project outwardly beyond the circumference of the rod to engage the outer end of the pipe, teeth formed on the inner edge of the sleeve for engagement with the outer 20 end of the pipe, a nut threaded to the re-

duced portion to force the teeth in the outer end of the pipe and to frictionally lock the sleeve against rotation, a second sleeve located on the rod and of a smaller diameter than the pipe, teeth formed on the outer edge 25 of the second sleeve to engage the pipe, a square supporting sleeve formed on the second sleeve to be gripped by a vise, a nut threaded to the rod and engaging the supporting sleeve for forcing the teeth on the 30 second sleeve to engage the pipe and cooperate with the first mentioned nut to lock the pipe against rotation.

In testimony whereof I affix my signature in presence of two witnesses.

ROBERT J. MITCHELL.
